UNITED STATES PATENT OFFICE.

JOHN A. WHITTINGTON, OF ATLANTA, GEORGIA.

PRINTING DEVICE.

1,292,190.

Specification of Letters Patent. Patented Jan. 21, 1919.

Application filed October 9, 1917. Serial No. 195,565.

To all whom it may concern:

Be it known that I, JOHN A. WHITTINGTON, a citizen of the United States, residing at Atlanta, in the county of Fulton and 5 State of Georgia, have invented certain new and useful Improvements in Printing Devices; and I do hereby declare the following to be a full, clear, and exact description of the invention, such as will enable others 10 skilled in the art to which it appertains to make and use the same.

This invention relates to devices for printing in more than one color and the primary object of the invention is to provide a type 15 chase for multicolor printing which is simple in construction, effective in use and not liable to easy displacement of parts.

In such devices, means are provided for printing from different lines of type in different colors at a single operation, or with a 20 single compression and for this reason it is necessary to so manipulate the different lines of type and the means for inking such lines, that different colors of ink will be placed on 25 the different lines without interference with each other, and in carrying out the object of the invention I provide improved means for such purposes.

With the expressed general object of the 30 invention in view, my invention consists in the improved construction, arrangement and combination of parts hereinafter fully described and afterward specifically claimed.

In order that the construction and operation thereof may be readily comprehended, I have illustrated an approved embodiment 35 of my invention in the accompanying drawings and will now proceed to specifically describe the same in connection with said drawings in which—

Figure 1 represents the device in plan view with the parts in printing position.

Fig. 2, a plan view with one type frame removed from printing position into re- 40 leased or inactive position,

Fig. 3, a view similar to Fig. 2, with the ink tank removed,

Fig. 4, a view in side elevation with one of the end plates of the outer frame removed,

50 Fig. 5, an enlarged, right hand end view of the parts shown in Fig. 4,

Fig. 6, a view similar to Fig. 5 with the lever removed,

Fig. 7, a sectional view on the transverse plane indicated by the dotted line 7—7 of 55 Fig. 4,

Fig. 8, a central, transverse, sectional view,

Fig. 9, a longitudinal, sectional view on the vertical plane indicated by the dotted line 9—9 of Fig. 8, and

Fig. 10, a detail elevational end view showing the support for the ink tank in connection with the type plate.

Like reference characters indicate the same parts in all of the figures of the drawing. 65

Referring specifically to the drawings 12 indicates the outer, box like structure, comprising two substantially U-shaped halves or end plates 13, 14, in which a tripper frame 15 is mounted which telescopically carries 70 an inner frame 16, the tripper frame 15 being normally held above type level, or above the box 12, as seen in Figs. 5 and 8 and hereinafter explained.

The end U-shaped plates 13 and 14 of the box 12 are secured to the bottom by suitable means such as screws 17, as seen on Fig. 8, passing into upright flanges 18 of the bottom.

The frame 16 is recessed in its upper face, 80 as at 19, Figs. 7 and 8, to receive an electro-plate 20, a slide 21 in one side of the recess, backed by a spring 22, serving to permit of the ready removal of the plate, and springs 23 keeping the plate pressed outward to 85 maintain it in upper position.

At each end of the machine are two levers 24 which have intermeshing teeth or cogs at their inner ends so that they must move simultaneously on their pivots 25. These 90 levers are pivotally connected also to the frame 15 by pins 26 and by reason of these connections, the frame 15 will be compelled to move in a level position, when pressure is applied to it as hereinafter explained.

A lever 27 is mounted pivotally on the frame 16 by a pin 28 which passes through a vertical slot 29 in the frame 15 and also receives in a longitudinal slot 30 at its outer end a pin 31 projecting eccentrically from a disk 32, the latter being mounted pivotally on a pin or shaft 33 which pivotally carries 100

a frame or bar 34 in which is removably securable, by a screw 35, an electrotype 36 intended to receive ink of a different color from that of the electrotype 20.

5 This lever 27 is normally and yieldingly pressed upward by a spring 37 and carries in its upper surface a bumper 38 which contacts with a block 39 carried by the frame 15 and normally pressed downward by 10 springs 40.

15 A cam piece 41 depends from the electroplate 20 (see Figs. 8, 9 and 10) the front edge 42 of which is inclined to bear against a roller 43 carried by an upright 44 secured to the support 45 of an ink tank 46, which tank has its end supplied with perforations 47 to permit the color ink carried in the tank to ooze through to a porous inking pad 48 by which the ink is taken in and supplied 20 to the electrotype 36 carried by the frame or bar 34, such contact of the electrotype and the inking pad taking place when the electrotype 20, is depressed against the tension of the springs 23 by the inking rollers of the 25 press, causing the inclined edge of the cam piece to move the ink tank and the inking pad against the electrotype 36 while in its inactive position as in Fig. 8.

30 The ink tank has a suitable stopper and also has depressions 49 in its upper surface into which project side flanges 50 whereby the tank can be raised and removed by placing the thumb and finger in the depressions and clasping the flanges. The electrotype 35 20 is normally and yieldingly held slightly above type level, and above the tank and pad, by the springs 23, and the ink tank, and with it the ink pad, are normally and yieldingly upheld by springs 51, and are thus 40 automatically moved away from the type 36 when pressure is removed.

35 In its lower or inking position, the type bar 34 rests on an elastic bumper 52 which serves to prevent jar or shock when the bar 45 is turned on the shaft 33 to its lower position and said bar 34 is normally yieldingly held in its lower position by a spring 53 attached to and coiled about the shaft 33 and having its outer end pressing against the 50 bar 34, as seen in Fig. 8.

The construction and arrangement of the parts of my invention will be readily understood from the foregoing and the operation may be summarized as follows:

55 In the use of the device and after it has been set up in the regular form, the inking rollers pass over it, and ink and slightly depress the electroplate 20 which in turn moves the inking pad 48 into engagement 60 with and inks the type bar 36. Immediately after the inking rollers have passed over the device, the various parts return to their normal position.

Since the tension of the springs 37 is

greater than the force applied to the inking 65 rollers, the tripper frame 15 will remain in its normal position; therefore, in order that the inking roller may engage and ink the electroplate 20, it will, by reason of its composition, yield at the points of contact with 70 the frame 15.

75 After the electroplate and the type bar have been inked, the paper carrying plate or frame of the press will move into engagement with the tripper frame and since the power applied to the paper carrying plate is greater than the strength of the springs 37, the tripper frame will necessarily be depressed. This depression of the tripper frame will actuate the levers 27 which in turn 80 will through their connections rock the type bar 36 upwardly into printing position.

85 The type bar 34 has an axle 33 through it and can be turned on this axle against the tension of the spring which is connected to that shaft and the bar. It will be noticed that when the type bar 34 is stopped in perpendicular position, the tripper frame 15 has been forced down, but has not quite reached type level. It is therefore necessary for the 90 spring between the type bar 34 and its axle to yield a little to allow this tripper frame to reach type level. The reason for having this double spring arrangement is for the 95 type bar to stop moving before the paper comes in contact with it. This is necessary, for should the paper come in contact with the moving type the ink would be smeared on the paper instead of making a clear impression.

100 I have shown an electrotype 36, but I may use special type with short stems instead. Such type may be set in the slot where the electrotype 36 is now held, and secured by a set screw or other means. This will enable the printer to change the wording of the line (to be printed in color) at will.

105 On a newspaper press the blank paper is wrapped around a steel cylinder and the cylinder rolls over the flat bed of type, in 110 which the device is inserted, and approaches from any of the four sides. My machine, with the tripper frame 15 extending all around, will work on a press of this kind. The machine will not only operate from any 115 side, but the frame will be held down until the cylinder carrying the paper has passed entirely over the machine, thereby preventing the type line from moving while the paper is in contact with it.

120 I have specifically described the construction, arrangement and combination of the parts but I do not confine myself to the same, but hold that slight changes or variations therefrom may be made without avoiding the scope of the claims or departing from the spirit of the invention.

125 Having thus fully described my inven-

tion, what I claim as new and desire to secure by Letters Patent of the United States, is:

1. A type chase for multiplex printing comprising a tripper frame, normally held above type level, a stationary frame telescoped in the tripper frame, a printing frame carried by said stationary frame and normally held below the tripper frame, a type bar pivoted in the stationary frame and normally in a lowered or inactive position, and connections whereby the lowering of the tripper frame will bring the type bar into printing position. 65
- 15 2. A type chase for multiplex printing comprising a vertically movable printing frame, a type bar pivotally mounted, and normally held in lowered or inactive position, an inking pad adjacent to the type of the type bar when in its normal position, and means whereby the depression of the printing frame will actuate the pad to ink the type of the type bar. 70
- 20 3. A type chase for multiplex printing comprising a vertically movable printing frame, a type bar pivotally mounted, and normally held in lowered or inactive position, an inking pad adjacent to the type of the type bar when in its normal position, and means whereby the depression of the printing frame will actuate the pad to ink the type of the type bar, and to withdraw the pad therefrom. 75
- 25 4. A type chase for multiplex printing comprising a vertically movable printing frame, a type bar pivotally mounted, and normally held in lowered or inactive position, an inking pad adjacent to the type of the type bar when in its normal position, and means whereby the depression of the printing frame will actuate the pad to ink the type of the type bar, and to withdraw the pad therefrom. 80
- 30 5. A type chase for multiplex printing comprising a vertically movable printing frame, a type bar pivotally mounted, and normally held in lowered or inactive position, an inking pad adjacent to the type of the type bar when in its normal position, an ink tank adjacent to the inking pad and supplying ink thereto, and means whereby the depression of the printing frame will move the ink tank and pad to bring the latter into contact with the type of the type bar. 85
- 35 6. A type chase for multiplex printing comprising a vertically movable printing frame, a type bar pivotally mounted, and normally held in lowered or inactive position, an inking pad adjacent to the type of the type bar when in its normal position, an ink tank adjacent to the inking pad and supplying ink thereto, and means whereby the depression of the printing frame will move the ink tank and pad to bring the latter into contact with the type of the type bar. 90
- 40 7. A type chase for multiplex printing comprising a tripper frame, a block below the tripper frame, springs between the frame and block tending to press the block downward and the frame upward, a pivoted lever below and contacting with the block, a spring under the free end of the lever, a pivoted type bar, and connections between the lever and the type bar whereby the depression of the frame will tilt the type bar to printing position. 95
- 45 8. A type chase for multiplex printing comprising a tripper frame, a block below the tripper frame, springs between the frame and block tending to press the block downward and the frame upward, a pivoted lever below and contacting with the block, a spring under the free end of the lever, a pivoted type bar, and connections between the lever and the type bar whereby the depression of the frame will tilt the type bar to printing position, said connections comprising a disk, a pivot therefor forming also the shaft of the type bar, and an eccentric pin on the disk engaging in a longitudinal slot in the free end of the lever. 100
- 50 9. A type chase for multiplex printing comprising a tripper frame, a block below the tripper frame, springs between the frame and block tending to press the block downward and the frame upward, a pivoted lever below and contacting with the block, a disk, an eccentric pin on the disk engaging in a slot in the free end of the lever, a pivoted type bar, a shaft supporting both the disk and the type bar, and a spring secured to and coiled about the shaft and having its free end tangentially extended and engaging the type bar with a tendency to press it yieldingly toward its lower or inactive position. 105
- 55 10. A type chase for multiplex printing comprising a tripper frame vertically movable, having a vertical slot, a stationary frame telescoped in the tripper frame, a pin projecting from the stationary frame through the slot in the tripper frame, a lever centrally under the tripper frame pivoted on said pin and having yielding 110
- 60 11. A type chase for multiplex printing comprising a tripper frame vertically movable, having a vertical slot, a stationary frame telescoped in the tripper frame, a pin projecting from the stationary frame through the slot in the tripper frame, a lever centrally under the tripper frame pivoted on said pin and having yielding 115
- 65 12. A type chase for multiplex printing comprising a tripper frame vertically movable, having a vertical slot, a stationary frame telescoped in the tripper frame, a pin projecting from the stationary frame through the slot in the tripper frame, a lever centrally under the tripper frame pivoted on said pin and having yielding 120
- 70 13. A type chase for multiplex printing comprising a tripper frame vertically movable, having a vertical slot, a stationary frame telescoped in the tripper frame, a pin projecting from the stationary frame through the slot in the tripper frame, a lever centrally under the tripper frame pivoted on said pin and having yielding 125

contact with the tripper frame when said frame is depressed, a pivoted type bar, and connections between the lever and type bar for operating the type bar on its pivot.

- 5 11. A type chase for multiplex printing comprising a vertically movable tripper frame, a stationary frame telescoped within the tripper frame, and two levers pivotally connected at their outer ends to the tripper
10 frame and at their mid-lengths to the sta-

tionary frame and provided at their inner ends with intermeshing teeth.

In testimony whereof I have signed my name to this specification in the presence of two subscribing witnesses.

JOHN A. WHITTINGTON.
